Primary Examiner — Rosemary K Tarca
Assistant Examiner — Yolanda Robinson(57) **CLAIM**

The ornamental design for a cigar cutter incorporating a bottle opener and keychain attachment, as shown and described.

DESCRIPTION

FIG. 1 is a top perspective view of a cigar cutter incorporating a bottle opener and keychain attachment;
 FIG. 2 is a top plan view thereof;
 FIG. 3 is a bottom plan view thereof;
 FIG. 4 is a front elevation view thereof;
 FIG. 5 is a back elevation view thereof;
 FIG. 6 is a left elevation view thereof;
 FIG. 7 is a right elevation view thereof; and,
 FIG. 8 is a top view thereof; shown in a state of use.
 The broken lines showing a bottle and bottle cap depict environmental subject matter only and form no part of the claimed design.
